(57) **CLAIM**

The design for an element for adhesive thermometer, as shown and described.

DESCRIPTION

FIG. 1 is a front perspective view of an element for an adhesive thermometer showing our new design;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view of the design; and,

FIG. 8 is a front perspective view showing in dashed lines an environment in which the element can be used.
